UNITED STATES PATENT OFFICE.

WILLIAM HENRY BRUNDAGE, OF HUDSON, NEW YORK.

STORE-SERVICE APPARATUS.

SPECIFICATION forming part of Letters Patent No. 593,458, dated November 9, 1897.

Application filed December 10, 1896. Serial No. 615,079. (No model.)

To all whom it may concern:

Be it known that I, WILLIAM HENRY BRUNDAGE, of Hudson, in the county of Columbia and State of New York, have invented certain new and useful Improvements in Store-Service Apparatus, of which the following is a full, clear, and exact description.

The object of my invention is to provide certain new and useful improvements in store-service apparatus, whereby the carriage is propelled in a simple and effective manner without the use of previously-stored-up power and received and securely held in the receiving end without much jar to the apparatus.

15 The invention consists principally of a spring-pressed picker-stick adapted to engage and move the carriage backward into a propelling position and a compound-lever mechanism for drawing the said picker-stick rearward with the carriage into a propelling position and then suddenly releasing the stick to send the carriage over the line.

The invention also consists of certain parts and details and combinations of the same, as 25 will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement. Fig. 2 is a plan view of the same with the carriage at the receiving end. Fig. 3 is an enlarged sectional side elevation of the carriage. Fig. 4 is a transverse section of the same on the line 4-4 of Fig. 3. Fig. 5 is a transverse section of the ball-bearing for the carriage. Fig. 6 is an enlarged end elevation of the receiver, and Fig. 7 is a plan view of a 40 modified form of carriage.

The improved apparatus is provided with a standard A, fastened to the ceiling or other support, and carrying one end of an inclined wireway B, the other end of which is supported in any desired manner, the wire being stretched tight between the two supports, so as to permit of readily propelling the carriage C over the wire. The carriage C is provided with a suitable removable money-box D, as 45 indicated in the drawings.

On the lower end of the standard A is formed a block A', on which is fulcrumed at E' a

picker-stick E, extending upwardly and forwardly, to straddle with its forked free end E² the wireway B, the said forked end being 55 adapted to engage a staple C', projecting longitudinally from the rear end of the carriage C. A lug A² on the block A' limits the outward swinging motion of the picker-stick E, and the latter is formed on its back with a 60 guide-arm E³, fastened at its lower end on a transverse bar E⁴, rigidly secured to the picker-stick E near its pivot end E'. Rods F extend through openings in the bar E⁴, and the rods are fulcrumed at F' to the standard 65 A, and on each rod is coiled a spring F², resting with its forward end on the cross-bar E⁴ and at its rear end on a collar F³ or nut adjustably secured to the corresponding rod F, to permit of regulating the tension of the 70 springs according to the force required to send the carriage over a short or long wireway.

The guide-arm E³ is adapted to be engaged by a friction-roller G, journaled on a transversely-extending pin G', carried by the free 75 end of a lever H, formed on its lower end with a handle H', adapted to be taken hold of by the operator when actuating the apparatus for sending the carriage C over the wireway B by the picker-stick E, as hereinafter more 80 fully described.

The lever H is curved, as indicated in Fig. 1, and is formed at its curved portion with a slot H², engaged by a pin or friction-roller I, held on a bracket A³, extending from the 85 standard A. The pin or roller I forms a fulcrum for the lever H to swing on and also a guide for moving the lever downward, so as to engage the friction-roller G with the guide-arm E³ between the guide-arm and the back 90 of the picker-stick E. The pin G' is pivotally connected with toggle-lever links J and J', pivotally connected by links J² J³ with a pin J⁴, held on the standard A³. A spring J⁵ is attached at one end to the standard A and 95 presses with its other end on one of the links of the toggle-lever, so as to hold the latter normally in a closed position and to assist in closing the same after the toggle-lever has been opened by the action of the lever H and 100 after the picker-stick E has been released and the carriage C sent over the line to return the said lever H to its normal position. (Shown in full lines, Fig. 1.)

The carriage C has a longitudinal bore for the passage of the wireway B and is provided with a hinged cover C², adapted to be locked to the body by a suitable catch K, as illustrated in Figs. 1 and 4.

In the carriage C is secured a cylindrical bushing L, supporting grooved wheels N, engaging the wireway B at the top and bottom, the said wheels being located approximately near the middle of the carriage, as is plainly shown in Fig. 3. In order to reduce the friction of the carriage traveling on the wireway B, I provide ball-bearings comprising balls O, surrounding the wireway B and held in chambers L', formed transversely in the cylindrical bushing L. (See Fig. 3.)

Now it will be seen that by the arrangement described the wireway B extends through the carriage C and is engaged by the balls O and the grooved wheels N, whereby the friction will be reduced and the tendency of the carriage to sway transversely during its movement from one point to another is in a measure counteracted.

At the receiving end of the apparatus is arranged a device P for engaging and holding the front end of the carriage, so as to prevent undue jar to the whole apparatus and securely hold the carriage in place after it reaches said end. This device P is preferably made with two sections P' and P², engaging the wireway B and securely clamped thereto at any desired point by a suitable clip Q. (Shown in Figs 1 and 6.)

From one or both ends of the sections P' and P² extend the curved gripping-arms P³, preferably four in number and each formed at its outer end with a ball P⁴, adapted to travel up the conical end C⁴ of the carriage, to pass over an annular ridge or bead C³ and fall in behind the latter, so as to securely hold the carriage in place at the end of the line, as indicated in Fig. 2. Thus when the carriage C is propelled to the end of the line the conical end C⁴ passes in between the several balls P⁴ and opens the arms P³ until the balls finally pass over and behind the ridge C³ to securely hold the carriage in place and prevent its rebounding.

The operation is as follows: When the several parts are in the position illustrated in Fig. 1, then the picker-stick E is in its normal outermost position and the carriage C rests with its rear end against the free end of the picker-stick. When it is desired to propel the carriage C forward, then the operator pulls the lever H downward, so that the friction-roller G passes to the front of the guide-arm E³, between the latter and the back of the picker-stick E, as shown in dot-and-dash lines in Fig. 1. In doing so the toggle-lever, composed of the links J J' J² J³, opens, and the operator then on swinging the handle H' forward in the direction of the arrow a' causes a rearward swinging of the picker-stick E, so that the free end thereof engages the staple C' and carries the carriage C rearward into a

propelling position, as indicated in dotted lines in Fig. 1. By the operator swinging the picker-stick E rearward, as described, the springs F² on the rods F are compressed, and the operator on further pulling the lever H forward in the direction of the arrow a' finally draws the friction-roller G over the free end of the guide-arm E³, so that the latter is released, and with it the picker-stick E, and the latter by the force of the springs F² is suddenly and forcibly swung outward in the direction of the arrow a' to forcibly propel the carriage C forward along the wireway B. Now it will be seen that when the picker-stick E swings forward and pushes on the carriage C the free end of the picker-stick finally becomes disengaged from the staple C', so that the carriage C travels forward on the unobstructed wireway B. When the carriage reaches the receiving end, it passes, with its conical end C⁴, into the wire arms P³, as previously described, to interrupt the movement of the carriage and to securely hold the same in place.

Instead of using a staple C' on the carriage C, I may use other means. For instance, as shown in Fig. 7, I provide the carriage C⁵ at its rear end with arms C⁶, having inwardly and forwardly projecting spring-tongues C⁷, adapted to be engaged by the free forked end E² of the picker-stick E. The action of the picker-stick E on the spring-tongues is similar to the one described in reference to the staple C'.

Having thus fully described my invention, I claim as new and desire to secure by Letters Patent—

1. A store-service apparatus, provided with a pivoted and spring-pressed picker-stick, and means for drawing the picker-stick rearwardly to compress its spring and to then suddenly release the said stick, substantially as and for the purpose set forth. 105

2. A store-service apparatus, comprising a pivoted and spring-pressed picker-stick, and a lever mechanism for drawing the picker-stick rearwardly to compress its spring and to then suddenly release the said stick, substantially as described. 110

3. A store-service apparatus, comprising a pivoted and spring-pressed picker-stick, a guide-arm on said picker-stick, a lever adapted to engage the guide-arm of the picker-stick 120 to draw the stick rearward to compress its spring, and means for releasing the lever from the said arm after the stick has been drawn rearward, substantially as described.

4. A store-service apparatus, comprising a pivoted and spring-pressed picker-stick, a guide-arm on the picker-stick, a lever adapted to engage the guide-arm of the picker-stick to move the picker-stick rearward to compress its spring, and a toggle-lever connected with the lever, substantially as described. 125

5. A store-service apparatus, comprising a pivoted and spring-pressed picker-stick for propelling the carriage over the line, a guide-

arm on the said picker-stick, a lever mounted to swing and to slide and carrying a friction-roller for engagement with the said guide-arm, and a toggle-lever connected with the 5 said lever, as set forth.

6. A store-service apparatus, comprising a support, a pivoted picker-stick, a transverse bar secured to the pivoted end of the said stick, a guide-arm secured to the said bar, 10 rods fulcrumed on the support and projecting through openings in the transverse bars, coiled springs on the rods between shoulders thereon and the transverse bar, and means for swinging the picker-stick on its pivot to 15 compress the said springs and then to suddenly release the stick, substantially as described.

7. A store-service apparatus, comprising a support, a picker-stick pivoted to the sup-

port, a transverse bar secured to the picker- 20 stick, a guide-arm secured to the said bar, rods pivoted to the support and projecting through openings in the transverse bar, springs on the rods, a pivoted and sliding lever, the upper end of the lever being adapted 25 to engage the guide-arm, and a toggle connected with the upper end of the said lever, substantially as herein shown and described.

8. In a store-service apparatus, a carriage having a central longitudinal bore, ball-bear- 30 ings, and oppositely-disposed grooved wheels, said bearings and wheels being arranged adjacent to said longitudinal bore, substantially as shown and described.
